Inventor:
Frank Smith

UNITED STATES PATENT OFFICE.

FRANK SMITH, OF CLINTON, MISSOURI.

WRENCH.

1,284,802.

Specification of Letters Patent. Patented Nov. 12, 1918.

Application filed July 8, 1918. Serial No. 243,913.

To all whom it may concern:

Be it known that I, FRANK SMITH, a citizen of the United States, residing at Clinton, in the county of Henry and State of Missouri, have invented certain new and useful Improvements in Wrenches; and I do declare the following to be a full, clear, and exact description of the invention, such as will enable others skilled in the art to which

10 it appertains to make and use the same.

My invention relates to improvements in wrenches; and it consists in the novel construction, combination, and arrangement of devices herein shown and described.

15 The object of the invention is to provide a more simple, durable, and efficient wrench which may be conveniently used as a pair of pliers, and for various other purposes.

The above and other objects which will 20 appear as the nature of my invention is better understood, are accomplished by means of the construction illustrated in the accompanying drawings, in which—

Figure 1 is a side view of my improved 25 wrench, showing the hand-lever in its normal position. Fig. 2 is a sectional view showing the lever swung outwardly. Fig. 3 is a sectional view taken on the line 1—1 of Fig. 1. Fig. 4 is a sliding catch or lock 30 for the hand-lever. Fig. 5 is a piece of tempered steel used as a spring.

Referring to my drawings by numerals, 35 8 denotes my improved wrench, which comprises a shank 4, having a fixed jaw 7, a slot 5 at each side of which for about one-half its length are threaded members 16, 17. Running slidably in this slot is a shaft 12, at one end of which is pivotally mounted a hand-lever 19, which has formed at one end 40 a jaw 20, and a longitudinal slot 21. Extending from this slot to the end of the hand-lever is a grooved center 22, which lies over a portion of the shank 4, when the hand-lever is in its normal position. In the shaft 45 12, is a slot 23, in which is the catch 2, and the spring 3, the grooved part of catch 2 extending over the spring at each side; the spring being formed in a curved manner serves to hold the catch 2 where placed. A

certain portion of catch 2, and spring 3, extending into the slot 21 of the lever 19, serves to hold the catch 2 and the spring 3 in the slot 23. The members 24, 25 of the catch 2, extend outward on opposite sides to form a lock when pushed forward into the recesses 10, 11 formed in the lever 19, the lever is locked in its normal position for use of the tool as a wrench.

Extending from one end of the shaft 12, is a pivot 27 extending through the center 60 portion of a screw 28, which is held on pivot 27 by a screw head 29, the threaded portion of the screw 28, running in the threaded members 16, 17. By turning the screw 28 to the right the jaw 20 will coat 65 with the jaw 7, and if to the left it will separate the jaws.

The construction, use, and advantages of the invention will be readily understood from the foregoing description, taken in 70 connection with the accompanying drawings. It will be seen that when the lever is locked and the tool is to be used as a wrench, the lever then forms a part of the handle of the wrench, thereby being out of 75 the way when used in close places. When the jaws are separated to receive a large nut, it will be observed that the same leverage may be applied as when the jaws are together. The movable jaw being a part of 80 the lever there is no chance for play when working on small or worn nuts. The adjusting screw operating in a thread at each of its opposite sides, is stronger, more durable and can not buckle. The wrench 85 can be made with less bulk, weight and cost for a given strength.

I am aware that prior to my invention wrenches with lever attachments have been used, I therefore do not claim the combination broadly; but what I claim as new, and desired to secure by Letters Patent, is—

A wrench comprising a shank having a fixed jaw at one end and having a longitudinal slot therein, part of which slot is 90 threaded, a shaft slidably engaged in said slot and provided with a rectangular opening, a screw swiveled on one end of said

shaft and adapted to engage the threads of said shank, a longitudinally grooved lever pivotally connected to said shaft and provided with a slot through which said shank is adapted to extend, said lever having recesses on either side, a jaw formed integral with said lever, a catch slidingly engaged in said rectangular opening in said shaft, said catch adapted when pushed forward to engage said recesses and thereby hold the lever in fixed position relative to the shank, and a spring frictionally engaged with said catch.

FRANK SMITH
